BLOCK CONSTRUCTION FOR BOILER
TUBES AND THE LIKEJohn Edward Biery, Grantwood, N. J., assignor
to Foster Wheeler Corporation, New York,
N. Y., a corporation of New York

Application July 14, 1931, Serial No. 550,677

6 Claims. (Cl. 122—6)

My invention relates to armor or refractory coverings for heat absorbing members such as water tubes of water tube boilers.

One object of the invention is to provide a simplified construction of multiple-piece adjustable armor block units. Another object is to provide an armor construction permitting wide variations between centers of tubes and wide variations in tube alignment. Still another object is to provide armor construction of the type referred to as applicable to straight or curved tubes.

Further objects and the nature and advantages of the invention will become apparent as the description proceeds.

On the accompanying drawing, I have shown one embodiment of the invention by way of illustration but it will be understood that the invention is not limited to the particular structure illustrated.

Referring to the drawing, which is to be considered as a part of this specification;

Fig. 1 is a cross-sectional view of a water wall embodying my invention and is taken on the line 1—1 of Fig. 2;

Fig. 2 is a cross-sectional view taken on the line 2—2 of Fig. 1 and on the line 2—2 of Fig. 3;

Fig. 3 is a cross-sectional view taken on the line 3—3 of Fig. 2; and

Fig. 4 is a perspective view of a block made in accordance with my invention.

Reference character 10 designates generally a water wall of a furnace or the like. Water wall 10 comprises a plurality of spaced tubes 11 which may be connected to a common drum 12. Drum 12 may be located outside of the furnace and tubes 11 pass through furnace wall 13. The portions of tubes 11 inside the furnace wall are provided with an armor 14 made of blocks of cast iron or other suitable refractory material. The space behind tubes 11 is ordinarily filled with a plastic refractory material 15 held in place by means of sheet metal or the like.

Armor 14 comprises block units 18. Each block unit in turn comprises a pair of refractory block members 19 and 20. Block members 19 and 20 are of identical form and have a rectangular front fire surface or face 21 and cylindrical tube receiving recesses 22 providing surfaces for contact with the tubes. The side or wall 17 of each block member opposite from tube receiving recesses 22 is preferably a plane surface and has a wedge-shaped recess 23 therein. One wall or surface 24 of this recess is inclined with respect to other walls of the block 55 and is preferably flat. The width of the recess

23 is substantially less than the width of the wall 17 in consequence of which the fire surface or face 21 is continuous and the wedging means hereinafter referred to is not exposed to the heat of the combustion gases or flame. A semi-circular groove 25 extends from the rear face of the block into recess 23.

The two blocks 19 and 20, forming a block unit 18, are mounted forwardly on and between adjacent tubes with the side walls 17 and the recesses 23 of the respective blocks adjacent to each other as shown in Fig. 2. Before the blocks 19 and 20 are placed on the tubes a wedging member comprising a tapered head 26 and a shank 27 is placed between the blocks and in the recesses 23. The shank 27 extends through the opening formed by the grooves 25 in the block members.

A rigid backing member 28 having circular tube receiving recesses 16 is mounted rearwardly on tubes 11. Member 28 is provided with upper and lower flanges 29 between which extends a bridge portion or member 30. Bridge portion 30 is provided with an opening 31 which, when the rigid backing member is in place on the tubes, is in line with shank 27. Shank 27 is threaded at the end opposite to the tapered head, and the threaded portion extends through opening 31 and a nut 32 bearing against a washer 33 is threaded thereon.

When nut 32 is turned up it draws the wedge-shaped head 26 toward rigid backing member 28 and hence causes the wedge-shaped head to bear against the inclined walls 24 of the recesses 23 and hence to force blocks 19 and 20 apart 35 so that they are normally out of contact with each other. The side walls of the tapered head are preferably flat and are angularly disposed at the same angle as that between the adjacent walls 24 when the block members are mounted 40 as shown in Fig. 2 with walls 17 parallel. When the blocks are forced apart their tube receiving recesses 22 are forced in close contact with tubes 11.

Rigid backing members 28 are also provided 45 with flanges 34 at their ends. These flanges are formed with apertures 35 through which may be passed bolts 36. When all of the rigid backing members 28 in one row are secured together by means of bolts 36 there results a single rigid 50 backing member which extends the entire width of the water wall. The advantage of this is that when the blocks 19 and 20 are forced against the tubes there is a tendency to spread the tubes and this rigid backing member resists this tend- 55

ency. It is apparent that blocks 19 and 20 may be very readily secured to the tubes, requiring a minimum amount of time and labor. Moreover, these blocks are of a comparatively simple form and are cheap to cast.

5 My improved block unit is well adapted to be used on bent portions of the tubes, as at 37 or 38 on Fig. 1. For use under these conditions, the blocks are preferably made shorter than for use 10 on the straight portions of the tubes. Also the tube receiving recesses 22 are made curved in order to fit the bend in the pipe but no change is necessary in the rest of the block, including surface 21 and grooves 23.

15 My improved block unit and wedging means is applicable to a variety of heat absorbing apparatuses and to tubes for heating water, steam, oil or other fluids. It is applicable to any system of blocks 20 where intimate contact is required, adjustment is necessary or desired and expansion strains are to be taken care of.

It will be noted that the block members are not intended to swing on the tubes nor to normally bear on or to normally contact with each other but are designed to have straight movement. Obviously the wedging surface may be somewhat curved if desired and some rolling on the tubes may take place. I prefer, however, to, 30 have the block units and wedging members so designed as to give a spreading of the blocks parallel to the plane of the centers of the tubes; that is so that the front fire surfaces 21 are maintained in a single plane. The blocks may 35 be applied to other surfaces than tube surfaces and are readily adaptable to surfaces of various configurations.

The proportion of surface contact with the tube can consist of from 25 to 50% of the tube 40 surface. The intimacy of contact is maintained regardless of temperature conditions. The greater the expansion, the greater the pressure against the tubes. It will be seen that the blocks can be adapted to the tubes even though the tubes 45 are out of alignment and that they need not be used to force tubes to any given alignment. It will be readily seen that the application of blocks in accordance with the invention is particularly advantageous to curved portions of tubes. This 50 facilitates the application of blocks close to a header where tube holes vary, such as in certain chain grate stoker installations. The blocks can be applied in staggered arrangement, staggering each block to any desired angle.

55 While I have shown and described one embodiment of my invention for the purpose of illustration, it is to be understood that my invention may be embodied in a variety of other

structures. Among other variations, it will be understood that the tapered head 26 may be a separate member pivoted to the pin or shank 27.

What I claim is:

1. The combination with spaced tubes, of a 5 block unit mounted forwardly thereon and therebetween comprising two block members, said block members having continuous heat absorption faces and curved surfaces on one side contacting said tubes and opposite adjacent sides between 10 said tubes and normally out of contact with each other, said adjacent sides being recessed to provide rearwardly converging wedging surfaces, a rigid backing member mounted on and rearwardly of said tubes, and a wedging member 15 comprising a shank, a tapered head mounted on one end of said shank having rearwardly converging side surfaces adapted to contact said wedging surfaces, the extent of the recesses being such that the head of the wedging member is 20 protected by said heat absorption faces and adjusting means mounted on the other end of said shank adapted to exert pressure against said rigid member.

2. A block of the character set forth having a 25 flat front heat absorption face, a substantially plane wall at one side of said face having a recess providing a wedging surface at an angle to said wall, and cylindrically recessed at a rear corner remote from the recessed wall. 30

3. A block of the character set forth having a flat front heat absorption face, a substantially plane wall at one side of said face having a recess providing a wedging surface at an angle to said wall, said wedging surface being intersected 35 by a groove, and cylindrically recessed at a rear corner remote from the recessed wall.

4. A block of the character set forth having a flat front heat absorption face, a substantially plane wall at one side of said face having a recess disposed centrally of said wall and providing a wedging surface at an acute angle to said wall, said wedging surface being intersected by a groove, and cylindrically recessed at a rear corner remote from the recessed wall. 45

5. A block of the character set forth having a continuous heat absorption face, a wall at one side of the face having a recess providing a wedging surface disposed at an angle to the wall, and cylindrically recessed at a rear corner remote from the recessed wall. 50

6. A block of the character set forth having a continuous rectangular heat absorption face, a wall at one side of the face having a recess providing a wedging surface disposed at an angle to the wall, and cylindrically recessed at a rear corner remote from the recessed wall. 55

JOHN EDWARD BIERY
